UNITED STATES PATENT OFFICE.

FELIX GERTH, OF BERLIN-TEMPELHOF, GERMANY, ASSIGNOR TO C. LORENZ AKTIEN-
GESELLSCHAFT, OF BERLIN-TEMPELHOF, GERMANY.

HIGH-FREQUENCY ELECTRIC FURNACE.

Application filed March 24, 1926, Serial No. 96,942, and in Germany, March 30, 1925.

The present invention relates to electric furnaces suitable for heating or melting metals and of the type in which high frequency alternating current is passed through a heating coil located outside the crucible, and the metal contained in the crucible is heated by the eddy currents generated therein. If, in such a furnace, the heating coil 1 is merely wound around the cylindrically shaped crucible 2, in the manner indicated in Figure 1 of the accompanying drawing, there is considerable marginal dispersion or fringing of the magnetic field, as indicated by the dotted lines in the drawings, with the result that a comparatively large percentage of the lines of force does not permeate the metal within the crucible, thereby decreasing the efficiency of the furnace. It is the object of the present invention to overcome this disadvantage.

According to this invention the heating coil in a furnace of the type referred to is wound so that its turns decrease in diameter towards either or both of its ends, rendering it conformatory in contour to the contour of the crucible, the above-mentioned marginal dispersion or fringing of the magnetic field with respect to the metal to be heated in the crucible is minimized, or in other words, the energy expended in the coil is to a greater extent concentrated upon the metal to be heated.

In order that the invention may be clearly understood and readily carried into effect, it will now be described more fully with reference to Figures 2 to 3 of the accompanying drawing, in which Figure 1 is a view in elevation, the coil appearing in section of a cylindrical crucible with conventional winding, illustrating the dispersion of the magnetic field which occurs with such a winding; Figure 2 is a vertical section through a cylindrical crucible with a winding in accordance with the principle of my invention; and Figure 3 is a horizontal section through an elliptical crucible with a winding embodying the principle of my invention.

In the form of furnace depicted in Figure

2, the coil 1 is constituted by a cylindrical coil portion surrounding the body of the cylindrical crucible 2 and a flat coil portion placed underneath it and in contact with its bottom, and it will be seen that the turns of the latter-named coil portion are of gradually decreasing diameter.

The preferred form of furnace is shown in Figure 3 in which the furnace 2^a is of elliptical shape and fitted with a coil 1^a, the turns of which progressively decrease in diameter from the sides towards both ends of the crucible, thereby so dimensioning the turns with respect to those portions of the crucible which they embrace that the created lines of force will be properly proportioned and directed according to the transverse dimensions of that part of the crucible which each coil turn envelops. The dotted lines in Figures 2 and 3 indicate lines of magnetic force, and it is seen that the number permeating the metal within the crucible 2^a is increased in comparison with those indicated in Figure 1, without any perceptible fringing or marginal dispersion.

What I claim is:—

1. A high frequency electric furnace of the character described comprising in combination a crucible, and a heating coil embracing the crucible and wound so that at least certain of its turns decrease in diameter, rendering it conformatory in contour to the contour of the crucible, whereby marginal dispersion or fringing of the magnetic field is minimized and the number of lines of force permeating the crucible and producing the heating action is increased.

2. A high frequency electric furnace of the character described, comprising in combination an elliptical crucible, and a heating coil embracing the crucible and having its turns decreasing in diameter from the sides towards the ends of the crucible so as to conform to the contour of the crucible.

In testimony whereof I have affixed my signature.

FELIX GERTH.
